DRINKING FOUNTAIN ATTACHMENT FOR FAUCETS

William J. Knight, 2619 Greenfield, Arcadia, Calif.

Filed Dec. 29, 1961, Ser. No. 68,128

Term of patent 14 years

(Cl. D91—3)

FIG. 1

FIG. 3

FIG. 4

FIG. 2

FIGURE 1 is a perspective view of the drinking fountain attachment for faucets showing the new design;

FIGURE 2 is a reduced side elevational view of the article;

FIGURE 3 is a top plan view, thereof as shown in FIGURE 2; and

FIGURE 4 is a bottom plan view thereof.

The undisclosed side of the article is substantially the same in appearance as the side shown.

The aerator is shown in dotted lines in FIGURE 1 for illustrative purposes only.

I claim:

The ornamental design for a drinking fountain attachment for faucets, as shown and described.
